SPECIFICATION forming part of Design No. 16,671, dated May 4, 1886.

Application filed January 30, 1886. Serial No. 190,375. Term of patent 14 years.

To all whom it may concern:

Be it known that I, JOSEPH K. DAVISON, a citizen of the United States, residing in the city and county of Philadelphia, State of Pennsylvania, have invented and produced a new and original Design for a Badge, of which the following is a specification, reference being had to the accompanying drawing, forming part thereof.

10 The leading feature of my design for a badge is a star, with a central medallion of stars and ornametations, and distinctive ornamenti-

15 tions in the points of the star. A represents a star, which depends from a flag, B, and C represents an eagle, to which the upper end of the flag is attached. At the foot of the eagle are cross-cannons D, the eagle being the top of the badge and the star the bottom thereof. On the back of the 20 crossed cannon is a monogram of the letters "F C L." On the face of the star is a medallion, E, containing a circular row of stars, F, and a number of badges, G, of various army corps, as shown in the badge of the organization known as the "Grand Army of 25 the Republic." In certain points of the star are ornamenti- H J K, respectively. The ornamenti- 30 H is in the form of a sun-burst with cross-sabers within the same. The ornamenti- J is in the form of a guidon with 30 cross-sabers thereon and a carbine, from which the guidon depends. The ornamenti- K is of the form of a seven-pointed figure with a bar in the center and a halo around the same.
